US0D1097166S

(12) **United States Design Patent** (10) **Patent No.:** **US D1,097,166 S**
(45) **Date of Patent:** **** Oct. 7, 2025**

(54) **DERMATOLOGY ADHESIVE PATCH**

(71) Applicant: **DermTech, LLC**, San Diego, CA (US)

(72) Inventor: **John Dobak, III**, La Jolla, CA (US)

(73) Assignee: **DERMTECH, LLC**, San Diego, CA (US)

(**) Term: **15 Years**

(21) Appl. No.: **29/796,477**

(22) Filed: **Jun. 24, 2021**

Related U.S. Application Data

(63) Continuation of application No. 17/183,589, filed on Feb. 24, 2021, which is a continuation of application No. 17/002,676, filed on Aug. 25, 2020, which is a continuation of application No. 16/886,611, filed on May 28, 2020, which is a continuation of application No. 15/571,247, filed as application No. PCT/US2016/030287 on Apr. 29, 2016, now Pat. No. 10,709,428.
